SHEDDING MECHANISM

Application filed June 4, 1929. Serial No. 368,263.

This invention relates to shedding mechanism in the nature of a jacquard, and the object is to provide a smoothly operating, accurate and powerful mechanism.

5 The invention will be well understood by reference to the following description of the illustrative embodiment thereof shown by way of example in the accompanying drawings, wherein:—

10 Fig. 1 is a section in a longitudinal plane of the loom illustrating so much of the shedding mechanism as is necessary for an understanding of the invention, other parts of the loom being omitted; and

15 Fig. 2 is a similar section with the shed open and parts being broken away.

The mechanism herein shown, by way of example merely and without limitation thereto, is of the single lift type and forms a 20 close shed. Referring to Fig. 1 of the drawings, I utilize a series of heddles 5, each controlling one or more warps and herein shown as metal strips provided between their ends with a mail or eye 7 through which passes a 25 single warp. These heddles are shown guided for rectilinear vertical sliding movement in the upper and lower cross-bars 9 and 11 and may be provided with pins 13 adapted to rest on the cross-bar 9 which thus constitutes a rest board. In the embodiment of 30 the invention shown the heddles are disposed in a single line across the loom. By "heddle" in the ensuing claims I refer to a mechanism of this kind adapted positively to position 35 the warp or warps engaged therewith as it is itself moved and distinguish from a flexible "coupling" (such as that usually comprising neck cord, harness line, sleeper, mail, hanger and lingo) actuated in one direction 40 by a lingo or its equivalent.

Each heddle is provided with a displaceable stop in the form of a griff-engaging hook 15 pivoted thereto at 17, the spring 19 extending between the body of the hook and the off- 45 set arm 21 on the heddle serving to draw the pin 23 on the hook against the stop 25 on the heddle, thus maintaining the hook normally at a fixed position angularly relatively to the heddle, being that shown at the rear in Fig. 50 1, the corresponding heddle being broken

away and omitted in Fig. 2. In this position the hooks 15 may underlie the cross-beam 27 which serves to maintain the heddles in the depressed position, the warps controlled thereby then forming the bottom line of the 55 shed.

The hooks 15, when swung forward against the force of springs 19 to the left in Fig. 1, as shown by the nearer of said hooks in that figure, are adapted to engage over a vertically reciprocating griff bar 29 extending across the loom between upright rods 31 which are reciprocated, as by means of the eccentrics 33 at their lower ends. I prefer to arrange the parts in such manner that the resulting draft shall be substantially longitudinal of the heddles. Extending between the rods 31 I preferably provide a counter griff bar 35 which overlies fixed stops in the form of pins 37 projecting from the heddles 5. 60 When certain hooks 15 are selected by suitable pattern mechanism and swung over the griff bar 29, the eccentrics reciprocate rods 31 and the griff bar raises the selected heddles, as shown in Fig. 2, to form the top line of the 65 shed. The remaining heddles, not shown in said Figure, the hooks of which remain under the beam 27, remain and are held in depressed position to form the bottom line of 70 the shed. The rods 31 then descend and the counter griff bar 35 positively retracts the 75 heddles which have been raised to the position of Fig. 2. The hooks of those heddles which are not to be raised in the formation of the succeeding shed are free to leave the 80 griff bar 29 in the lower position of the same under the influence of their springs 19 and rock into position under beam 27.

The reciprocation of the griff bars is here- 85 in shown as positively effected by power under the influence of eccentrics 33, but the connection of the griff bars to their operating means might be a force-closed one. However, the griff mechanism serves in itself to actuate the heddles in both directions and the 90 lingoies of the ordinary jacquard are eliminated.

Herein I have shown the hooks 15 as operated by means of connecting rods or radius 95 links 39 pivoted thereto and to blocks 41 slide- 100

ble on plungers 43 which move in a cross-piece 45 and are adapted to be reciprocated therein by suitable pattern mechanism. The block 41 is herein shown as a short section of a channel, the flanges of which provide bearings on the plunger 43, and a suitable spring 47 is interposed between the plunger and the block so that when the plunger 43 is moved to the left in the figure, it operates through spring 47, which is stronger than spring 19, to swing the hook 15 over. This arrangement permits an easy motion and permits overthrow of the plungers 43. The plungers 43 are desirably disposed in a plane at an elevation half-way 15 between the lower and upper positions shown in Figs. 1 and 2 respectively of the point of connection of link 39 to hook 15 to minimize the thrust action of the former as it swings. However, the yielding connection through spring 47 permits the lifting motion without undue strain on the parts.

The plungers 43 may be operated by any suitable pattern mechanism, herein shown as the reciprocating, intermittently rotating "cylinder" or prism 49 on the faces of which are received the linked-together bars 51 carrying the pegs 53, the whole resembling in appearance a dobby harness chain. Provision is made for inserting pegs in each bar 30 corresponding to the various plungers. Where a peg is present it engages the end of the plunger when the cylinder is moved to the left as in Fig. 1, moving the plunger to the left and causing the corresponding hook 15 to be swung over griff bar 29. If the peg is absent, the corresponding plunger and heddle are unaffected, as shown at the rear of Fig. 1. As the griff bar rises, engaging the hooks, the cylinder may retreat and turn, 35 as shown in Fig. 2, so that at the next cycle of the parts another link of the chain will come into action when the cylinder again moves to the left. The cylinder need dwell in the forward position only long enough to permit the griff bar 29 effectively to engage with the hooks 15 in its upward stroke. As seen in Fig. 2, the hook has a bill defining a throat into which the bar enters to interlock therewith and prevent disengagement of the 40 hook by the stress of spring 19. It may then start to retreat and turn as the shed opens and the pick takes place. If the cylinder advances to engage the plungers before the heddles have resumed the position of Fig. 1, no harm is done. Those hooks which are again to be lifted remain in position over griff bar 29 without returning to normal position. Those hooks controlling warps which are to 45 be transferred to the bottom of the shed are positively drawn down by counter griff bar 35 until they snap back under beam 27. The forward edges of the hooks and the lower edge or griff bar 29 are preferably rounded off as shown in the figures so that hooks controlling 50 warps which are to be transferred from the

bottom to the top of the shed, if freed from beam 27 by the forward stroke of the pattern cylinder before griff bar 29 reaches its lowermost position of Fig. 1, may ride over the bar until free to swing in above it, this being effected without undue strain because of the yieldable connection of the hooks with the plungers through springs 47. Thus no dwell of the griff in stationary lower center position is required.

I am aware that the invention may be embodied in other specific forms without departing from the spirit or essential attributes thereof, and I therefore desire the present embodiment to be considered in all respects as so illustrative and not restrictive; reference being had to the appended claims rather than to the foregoing description to indicate the scope of the invention.

Claims:

1. A shedding mechanism comprising vertically reciprocable heddles, hooks pivoted thereto, a beam overlying the hooks, pattern mechanism for rocking selected hooks from beneath the beam, a griff bar for engaging the hooks to elevate the heddles, a counter griff bar engaging the heddles for returning the same, and means for reciprocating said bars in unison.

2. In combination with a series of heddles guided for vertical movement, a vertically reciprocating frame having upper and lower griff bars, projections from said heddles underlying the lower bar, spring-pressed hooks pivoted to said heddles, and pattern means for swinging selected hooks against their springs over said upper bar.

3. In combination with a series of heddles guided for vertical movement, a vertically reciprocating frame having upper and lower griff bars, projections from said heddles underlying the lower bar, spring-pressed hooks pivoted to said heddles, a beam beneath which the hooks are normally disposed, and pattern means for swinging selected hooks against their springs over said upper bar.

4. In combination with a series of heddles guided for vertical movement, a vertically reciprocating frame having upper and lower griff bars, projections from said heddles underlying the lower bar, hooks pivoted to said heddles and adapted alternatively to overlie the upper griff bar or lie away therefrom, a beam beneath which those hooks not overlying the griff bar are disposed and constituting means preventing upward motion of the heddles, means tending to move the hooks to one position, and pattern mechanism for moving selected hooks to the other position.

5. In a shedding mechanism a series of heddles guided for vertical sliding movement, griff-engaging hooks movably mounted thereon, pattern mechanism for selectively positioning the hooks, and a double acting griff

for raising and returning selected heddles respectively to open and close the shed.

6. In a shedding mechanism a series of heddles guided for vertical sliding movement, 5 griff-engaging hooks pivoted thereto, springs normally positioning said hooks at a fixed angle, plungers having a yieldable force transmitting connection to said hooks, and pattern mechanism cooperating with said 10 plungers to swing selected hooks against their springs and a griff for lifting the so shifted hooks.

7. In a shedding mechanism a series of heddles guided for vertical sliding movement 15 griff-engaging hooks pivoted thereto, springs normally positioning said hooks at a fixed angle, radius links connected to said hooks, plungers secured to said links and pattern mechanism cooperating with said plungers 20 to swing selected hooks against their springs and a griff for lifting the so shifted hooks, said plungers operating in a plane substantially midway between the raised and lowered positions of the point of connection of said 25 links to said hooks.

8. A shedding mechanism comprising a series of heddles, hooks pivoted thereto, springs between said hooks and heddles normally to swing the former to a fixed position, 30 a beam beneath which said hooks are retracted by the springs at the down position of the latter, a reciprocating griff for interlocking the hooks to raise the same, means acting briefly during a portion of the cycle of the 35 griff while it is adjacent its lowermost position for shifting selected hooks into the path of the griff, and a counter griff for retracting the heddles.

9. A shedding mechanism comprising a 40 series of heddles, hooks pivoted thereto, springs between said hooks and heddles normally to swing the former to a fixed position, a reciprocating griff for interlocking the hooks to raise the same, and means acting briefly 45 during a portion of the cycle of the griff while it is adjacent its lower position and through a yieldable connection for shifting selected hooks into the path of the griff, the upper portions of said hooks and the lower portion of 50 the griff being shaped to permit the descending griff to displace and pass shifted hooks.

10. A shedding mechanism comprising a 55 series of heddles, hooks pivoted thereto, springs between said hooks and heddles normally to swing the former to a fixed position, a reciprocating griff for interlocking the hooks to raise the same, means acting briefly 60 during a portion of the cycle of the griff while it is adjacent its lower position and through a yieldable connection for shifting selected hooks into the path of the griff, the upper portions of said hooks and the lower portion of 65 the griff being shaped to permit the descending griff to displace and pass shifted hooks.

hooks, and a counter griff acting on the heddle for retracting the same.

11. In a shedding mechanism a set of heddles having fixed and displaceable stops, reciprocating griff means operating between 70 said stops to engage in its respective phases alternately the fixed stop and a displaced stop and adapted to interlock with the displaced stop to retain it in displaced position, and pattern means for selectively displacing 75 said stops.

12. In a shedding mechanism a set of heddles having fixed and displaceable stops, reciprocating griff means operating between 80 said stops and passing from its downward to its upward phase substantially without dwell in stationary position, said means engaging in its respective phases the fixed stop and a displaced stop, and adapted to interlock with the displaced stop to retain it in 85 displaced position, and pattern means for selectively momentarily displacing said displaceable stops into the path of the griff means substantially at the lowermost position of the latter.

13. In combination with a series of heddle bars having hooks for engaging a griff, a series of plungers adapted to be engaged by pattern mechanism, blocks slideable on the 90 plungers, springs interposed between the plungers and blocks and connecting rods between said blocks and hooks.

14. In combination with a series of heddle bars, griff-engaging hooks pivoted thereto, springs normally supporting said hooks at 95 a fixed angle, and means for swinging the hooks against said springs comprising a series of plungers adapted to be engaged by pattern mechanism, blocks slideable on the plungers, springs interposed between the 100 plungers and blocks and connecting rods between said blocks and hooks.

15. In a shedding mechanism, in combination with a set of heddles, a griff reciprocating without substantial dwell at its lower 110 limit of movement, griff-engaging means carried by the heddles, pattern mechanism momentarily acting on said means substantially at the lower position of the griff to cause the griff to interlock selected heddles in its upward movement positively to reciprocate the same therewith substantially throughout its 115 succeeding cycle.

16. In a shedding mechanism a vertically guided rigid member for connection to a 120 warp, a griff-engaging hook pivoted thereto, a spring interposed between said member and the hook, a connecting rod pivoted to the hook, and a member adapted to be displaced by a pattern mechanism having a yielding 125 connection to said rod for transmitting force thereto.

17. In a shedding mechanism vertically guided rigid members for connection to the 130 warps, griff-engaging hooks pivoted thereto,

springs interposed between the members and hooks, selective means for shifting said hooks against the force of the springs, and a projection on said members underlying a counter griff.

5 18. In a shedding mechanism a vibrating griff, individual heddles for controlling warps, said heddles having provision for connecting them to the griff for positive movement thereby in both directions, means for selecting certain of said heddles for such connection and means interlocking the heddles not so selected to prevent them from moving.

15 19. In a shedding mechanism in combination with a reciprocating griff, heddles for controlling warps, said heddles being normally at rest to define one side of the open shed, and means for selectively causing engagement of certain of said heddles with the griff for positive movement thereby to the other side of the shed and back to normal position.

20 20. In a jacquard mechanism of the close shed type in combination with means for moving selected heddles to form the shed, warp-controlling heddles normally positively held against movement in a position defining one side of the shed and pattern means for positioning selected heddles relatively to the griff to be positively moved thereby to the other side of the shed.

25 21. In a shedding mechanism in combination with a vibrating griff, a plurality of heddles, means for selectively connecting certain heddles to the griff to be actuated thereby positively in both directions, said heddles when not so connected providing means for positively holding the corresponding warps at the lower side of the shed.

30 22. In a shedding mechanism in combination with a plurality of warp-controlling heddles, stationary means to prevent movement of the heddles from closed shed position and selective movable means for releasing heddles from said stationary means and moving them to open shed position.

35 23. In a shedding mechanism a heddle controlling one or more warps, a vibrating griff, means carried by the heddle for connection with the griff whereby the heddle is positively actuated in both directions by the griff, and a selective means briefly controlling said heddle-carried means for initially effecting its connection with the griff.

40 24. In a shedding mechanism a heddle having an eye for a warp, a stop with which the heddle is normally in contact to prevent its shedding movement and selective means to move the heddle out from engagement with said stop to allow shedding movement thereof.

45 In testimony whereof, I have signed my name to this specification.

60 65 GEORGE B. AMBLER.
